[57] CLAIM

The ornamental design for a top panel of a table, as shown and described.

DESCRIPTION

FIG. 1 is a perspective view of a top panel of a table showing my new design;

FIG. 2 is a front view thereof, the rear view being a mirror image thereof;

FIG. 3 is a right side view thereof, the left side view being a mirror image thereof;

FIG. 4 is a top view thereof; and,

FIG. 5 is a bottom view thereof.

The broken lines in FIGS. 1, 2, 3 and 5 are environmental only and form no part of the claimed design.
